TEXTILE FABRIC

Santo J. Lombardo, New York, N. Y., assignor to Advance Glove Manufacturing Company, Detroit, Mich., a corporation of Michigan

Application September 9, 1950, Serial No. 12,120

Term of patent 14 years

(Cl. D92—1)

To all whom it may concern:

Be it known that I, Santo J. Lombardo, a citizen of the United States, residing at New York, in the county of New York and State of New York, have invented a new, original, and ornamental Design for a Textile Fabric, of which the following is a specification, reference being had to the accompanying drawing, forming a part hereof.

The figure is a plan view of a textile fabric showing my new design. A design unit is outlined by broken lines and is repeated over the fabric as indicated.

I claim:

The ornamental design for a textile fabric, as shown and described.

SANTO J. LOMBARDO.
